Arthur C. Eckert, ATTY.

UNITED STATES PATENT OFFICE.

HERMAN A. BERGMANN, OF ST. LOUIS, MISSOURI.

PIPE-CLEANER TOOL.

1,145,966.

Specification of Letters Patent. Patented July 13, 1915.

Application filed November 5, 1914. Serial No. 870,611.

To all whom it may concern:

Be it known that I, HERMAN A. BERGMANN, a citizen of the United States, and resident of St. Louis, Missouri, have invented certain new and useful Improvements in Pipe-Cleaner Tools, of which the following is a specification containing a full, clear, and exact description, reference being had to the accompanying drawings, forming a part hereof.

My invention relates to improvements in "pipe cleaner tools."

The object of my invention is to provide a pipe cleaner for the exterior surface of a pipe or other convex surfaces, which will remove scale, dirt or other foreign substances from the exterior of a pipe in a minimum of time and with a minimum of effort by devising a tool which either manually or by means of power either by a longitudinal scraping action or by a radial reciprocating motion removes the foreign substances from one half of a pipe with each application in an even and definite manner—the blade of the cleaner being in perfect contact with the semiperiphery of the pipe at all times; this perfect contact not being disturbed by irregularities in the contour of a pipe or in the blade of the tool, caused by wear, etc.

The tools used at the present time are inefficient in that the blades do not come in perfect contact with the semiperiphery of a pipe and hence only scrape or clean a part of the semiperiphery of the pipe with each application of the tool when the pipe surface is irregular owing to the presence of foreign matter, or slightly deformed through wear or imperfection in manufacture, or when the blades become irregular in contour owing to wear; this necessitates the repetition of the operation of scraping on the same surface to perfectly remove scale and then removes it but partially and imperfectly. My invention obviates this difficulty by use of blades which automatically conform to the contour of the pipe.

With the above purposes in view, my invention consists in certain novel features of construction and arrangement of parts as will be hereinafter more fully described, pointed out in the claim and illustrated by the accompanying drawings, in which;

Figure 1. is a side elevation of a device constructed according to my invention, po-

sitioned on a pipe as when in use. Fig. 2. is an end elevation of the same similarly positioned relative to a pipe. Fig. 3. is a vertical section along the line 3—3 of Fig. 60. Fig. 4. is an end elevation of a modified form of my invention showing the blades in two positions.

Referring by numerals to the accompanying drawings, 1, designates any conventional pipe or object having a regular convex exterior surface, upon which my invention is to be used to remove scale, dirt, etc.

2. and 3. represent two pivoted blades, each blade being in the form of a quadrant 70 of a circle, the blade surfaces being arcuated inclined planes, inclining rearwardly—shown in Fig. 2. These blades are revolubly pivoted to the members 4 and 5 by means of the pivots 6 and 7. The members 4 and 5 75 are riveted together, with the plate 8 secured between them, at their upper extremities by the rivets 9. To the upper edge of the plate 8 is secured the cylindrical block 10; the block 10 and plate 8 are secured together by the frictional contact between them in the groove of the block 10 and the metal members 12, which pierce both the block 10 and the plate 8. To this device so far described is riveted the curved 80 rod 13 which passes through the members 4 and 5 as well as through the plate 8, protruding slightly beyond plate 4 at 14. To the opposite end of the curved rod 13 is attached the handle 15, which is of the conventional type. Approximately in the center of this curved rod is fastened the rest plate 16, which has its bottom edge arcuated 85 so as to lie flat on the pipe 1. It is so positioned and designed that it only forms a 90 perfect contact with the pipe 1 when the blades 2 and 3 are perpendicular to the pipe.

The operation of my pipe cleaner is as follows: The tool is placed on the pipe to be 100 cleaned, as shown in Figs. 1 and 2, the left hand of the operator resting on the block 10 and the right grasping the handle 15. While exerting a sufficient pressure downwardly on the tool to keep it in contact with the 105 pipe, it is pulled forward in the direction of the arrow on Fig. 1, thereby producing a scraping action on the pipe, loosing and removing any scale or dirt that may be present on the exterior pipe surface.

It is to be observed that the rotation of the blades 2 and 3 about the pivots 6 and 7

is greatly restricted by the right angle of the blades coming in contact with the lower edge of the plate 8. This movement must be just sufficient to permit the blades to come 5 form to the surface of the pipe. A differently proportioned tool will be necessary for various pipe sizes.

While my diagram and description refer to a hand tool, I do not wish to be limited 10 to manual operation, since the longitudinal motion of the tool on the pipe may be imparted by mechanical means.

Fig. 4 designates a modified form of my 15 invention to be used in cases where the scale or dirt adheres so tightly to the pipe that it cannot be removed by a scraping action. The blades 2 and 3 in the modified form are substantially of the same shape as in the preferred form—just described, with this 20 exception however, that the arcuated cutting edges of the blades are not simple inclined planes, but are double inclined planes meeting in the center of the arcuations in the cutting edges. The blades are likewise pivoted 25 by two pivots 6 and 7 onto the frame 16 which terminates at its other extremity in the rod 17. The rotation of the blades is limited in this modified form by the edge 18; this rotation being sufficient to bring 30 about the necessary conformity between the blades and the pipe. This modified form is used by hammering on the rod 17 by man-

ual or pneumatic means, impact of the blows dislodging any dirt or scale that may be present.

What I claim and mean to secure by Letters-Patent is:

In a tool of the class described, a frame, fixed and alining pivotal elements supported by the frame, means for applying pressure to said pivoted elements over aforesaid pivotal elements, means for moving the frame longitudinally of a pipe to be cleaned, means arranged to rest on the pipe being cleaned for holding said frame at a fixed 45 angle relative to the pipe, a pair of scraping tools, each having an arcuate edge, which edges normally conjointly form a substantially continuous cutting edge to act on the pipe being cleaned and which tools are 50 mounted on said pivoted elements intermediate their ends for rocking movements only; so that when one end of either tool meets a projection on the surface of the pipe, the other ends will be maintained in functionate positions. 55

In testimony whereof, I have signed my name to this specification, in presence of two subscribing witnesses.

HERMAN A. BERGMANN.
